METHOD OF FOLDING AND PACKAGING
SHIRTS

Stephen Lighter, Milwaukee, Wis.

Application November 12, 1947, Serial No. 785,232

2 Claims. (Cl. 93—168)

1

My present invention relates generally to improvements in the art of folding and wrapping shirts, and relates more specifically to an improved folded shirt package and to an improved method of and apparatus for producing the packages.

It is customary in most laundries to carefully fold men's shirts after they have been laundered, by utilizing a flat rectangular folding board of desired length initially applied to the upper back portion of each shirt, and about which the cuffs, sleeves and opposite sides of the shirt are folded laterally, while the tail portions of the garment are subsequently folded upwardly or longitudinally over the pre-folded sleeves portions resting upon the board. After such folding of each shirt has been thus effected, an envelope or shirt embracing band is applied to the folded shirt body and a collar retainer may also be applied to the shirt collar, whereupon the folding board may be withdrawn upwardly from within the completed package. This method of folding and packaging has been in vogue for many years in spite of the fact that the flat or plane folding boards heretofore employed, frequently caused the folded cuffs and sleeves to produce unsightly bulges and wrinkles at the bosom portions of the enwrapped shirts and thus marred the neat appearance of the final packages. Then too, the envelopes and retainer bands heretofore utilized to maintain the shirts in folded condition could not be conveniently applied without wrinkling the garments, and these retaining devices when in the form of a complete envelope were relatively costly, while the prior relatively narrow and less expensive retainer bands did not afford sufficient support of the lower portions of the enwrapped shirts.

It is therefore a primary object of the present invention to provide an improved method of folding and wrapping freshly laundered shirts or the like, with the aid of an improved folding board and retaining band, whereby an improved and highly aesthetic final package results, so that all of the above mentioned objections are eliminated.

Another important object of this invention is to provide an improved shirt folding board which may be utilized to rapidly and effectively fold shirts or similar garments in a manner whereby undue protrusion and wrinkling of the shirt bosoms is positively avoided, and with the aid of which the cuffs and folded sleeves are caused to reinforce and stiffen the folded garments so as to resist free flexing or bending of the packages.

A further important object of my present invention is to provide an improved folded shirt retainer which may be readily manufactured from durable stock with minimum waste and at moderate cost, and which may also be conveni-

2

ently applied to the folded shirts so as to retain the garments neatly folded while also maintaining the collars and other exposed portions of the enwrapped articles in reenforced condition.

Still another important object of the invention is to provide an improved mode of expediting the folding and wrapping of freshly laundered shirts in a manner whereby the successive garments may be quickly packed and are effectively protected during subsequent handling.

An additional object of my invention is to provide simple and inexpensive apparatus for facilitating shirt wrapping and packaging procedure, and which may be utilized by a novice to produce flat and unwrinkled folded shirt packages having the folds snugly confined within a relatively narrow retainer band.

These and other specific objects and advantages of the present invention will be apparent from the following detailed description.

A clear conception of the several steps involved in my new shirt packaging method, and of the construction and mode of utilizing my improved folding board and protective wrappers, may be had by referring to the drawings accompanying and forming a part of this specification wherein like reference characters designate the same or similar parts in the various views.

Fig. 1 is a perspective view of one of my improved shirt folding boards showing the same being initially applied to a fragment of the upper rear portion of a shirt the major portion of the sleeves of which have been broken away;

Fig. 2 is a similar perspective view of the assemblage shown in Fig. 1, but showing the shirt sleeves folded inwardly about their shoulder portions toward the folding board resting upon the upper back portion of the shirt, with the shirt cuffs flattened and reposing within the concavity of the board;

Fig. 3 is another similar perspective view of the same assemblage, but showing the left hand sleeve and the adjacent side of the shirt, folded inwardly over the cuffs and concavity of the folding board;

Fig. 4 is still another similar perspective view of the assemblage, but showing the right hand sleeve and side of the shirt, folded inwardly over the cuffs, folding board concavity and prefolded opposite side;

Fig. 5 is an additional perspective view of the shirt and folding board assemblage, showing the shirt tail folded within the medial section of the shirt and these shirt portions folded upwardly over the previously folded parts reposing upon the folding board;

Fig. 6 is a respective view of the front of the finally folded shirt of Fig. 5 still engaging the folding board, but with the assemblage inverted, and also showing one of my improved retainers

and protectors being applied to the shirt bosom;

Fig. 7 is another perspective view of the inverted assemblage of Fig. 6, but showing the protective retainer band moved downwardly over the shirt bosom and beneath the collar lapels;

Fig. 8 is still another perspective view of the inverted folding board and shirt assembly, showing the collar protector of the shirt retainer band finally applied to the collar;

Fig. 9 is a perspective view of the rear of the final shirt package, showing the folding board being removed or withdrawn longitudinally from its upper end; and

Fig. 10 is a front and side perspective view of the final package.

While the invention has been shown and described herein as being advantageously applicable for the purpose of packing freshly laundered men's shirts, it is not my desire or intent to unnecessarily limit the scope or utility of the improved method and apparatus by virtue of the restricted disclosure.

In accordance with my present improvement, I provide an improved shirt folding member or board 14 of predetermined shape and size, having an elongated concavity or concave surface 15 on one side, and a correspondingly elongated convexity or convex surface 16 on its opposite side. This board 14 may be formed of any relatively stiff sheet material such as metal, plastic, wood, or paper adapted to retain its desired shape, and may also be of suitable length depending upon the length of final package desired. The folding member is preferably rectangular in shape and the width of the folding board 14 may be approximately seven inches in order to produce final packages approximately eight inches wide, while the effective length may be either twelve inches in order to produce so-called "short-fold" packs, or sixteen inches for the production of "long-fold" packs. As illustrated in Figs. 1 to 9 inclusive, the folding board 14 may also be provided at its opposite sides with swing brackets or wire 17 pivotally suspended from brackets 18 secured to the board extension 19, and while these wires 17 facilitate lateral folding of the side portions of the shirts, they are not necessary and may be omitted.

I also preferably provide improved folded shirt embracing elements or bands 20 such as illustrated in Figs. 7 to 10 inclusive, each comprising a continuous ribbon of relatively stiff cardboard stock having front and rear walls 21, 22 interconnected at their opposite sides along fold lines 24, the front wall 21 being provided with a collar retainer plate 25 swingably connected to its upper edge by a central panel 26, and the rear wall 22 being provided with a downwardly projecting integral central apron lip 27. These wrapper bands 20 may be formed of unitary blanks adapted to be die cut in nested groups from strips or sheets of cardboard so as to result in minimum waste of stock, and each of these blanks may be folded and joined at its ends into continuous ribbon formation in any convenient manner, but preferably by having the joints 28 extend centrally of the lips 27 in order to reinforce and stiffen these lips. While the collar retainer assemblage associated with the front wall 21 and specifically illustrated, is of the general type shown in my prior Patent #2,243,350, granted May 27, 1941, this assemblage may also be varied to some extent, although the collar retaining plate 25 and panel 26 do cooperate with the wrapper band 20 to maintain the latter in proper

position and to protect the enwrapped garment. The bands 20 are preferably formed of relatively resilient stock so that they may be distended into approximately elliptical shape preparatory to application to a shirt, and will clamp the shirt folds together when in final position.

When utilizing my improved folding member or board 14 and band 20 to carry on my improved method of packing a laundered shirt 30, the garment should be initially spread out upon a table or other suitable support with the back 31 uppermost and the sleeves 32 and cuffs 33 flattened and stretched outwardly as in Fig. 1; whereupon the folding board assemblage should be applied as shown with its convex face 16 resting upon the upper portion of the shirt back 31 and its concavity 15 upwardly directed, and with the folding wires 17 swung outwardly. With the elements thus positioned, the sleeves 32 and cuffs 33 of the shirt 30 should be folded about the distended wires 17 and the cuffs 33 together with the adjacent sleeve extremities should be caused to repose neatly within the concavity 15 of the folding board 14 as illustrated in Fig. 2, with the flattened cuffs 33 extending longitudinally of the board and superimposed upon each other.

The sleeves 32 and the side portions 34 of the shirt 30 may thereafter be folded inwardly in succession about the opposite side edges of the folding board 14, as depicted in Figs. 3 and 4, so that these side portions 34 become superimposed upon each other and upon the flat cuffs 33 and neatly folded sleeves 32, and these side folds should be extended throughout the entire length of the garment. Upon completion of this longitudinal folding operation, the tail portion 35 of the shirt 30 should be folded transversely and caused to repose upon the medial shirt portion 36, and the latter should thereafter be folded about the lower edge of the board 14 and deposited upon the inwardly pre-folded upper side portions 34 of the garment, as shown in Fig. 5. This completes the folding steps, and while the folding wires 17 may be utilized in order to facilitate folding of the sleeves 32 and side portions 34, their use is not essential.

In order to apply the final wrapper and retainer, the folding board and folded shirt assemblage may be disposed vertically with the board extension 19 resting upon a suitable support, whereupon a wrapper element or band 20 may be readily applied to the uppermost end of the assembly as illustrated in Fig. 6. The front and rear walls 21, 22 of the band 20 will be spread apart as the wrapper is slid downwardly over the bosom 31 and medial portion 36 of the folded garment, thereby drawing the fold lines 24 inwardly toward each other; and as the wrapping band 20 approaches the shirt collar 38, it should be permitted to pass beneath the collar lapels 39 while the retainer plate 25 should be allowed to advance over these lapels 39 and over the collar 38 as depicted in Fig. 7. The panel 26 will permit such action to take place during lowering of the band, and the retainer plate 25 may then be snapped into the interior of the collar 38 in the manner shown in Fig. 8.

The package may thereafter be freely withdrawn from the folding board 14 as illustrated in Fig. 9, whereupon the resilient wrapper band 20 will distend outwardly and will snugly embrace the body of the shirt 30, while the retainer plate 25 will prevent shifting of the band 20 along the shirt and will also protect the collar 38 against collapse. The apron projection 27

at the rear of the package extends downwardly away from the collar 38 and thus cooperates with the collar retainer and with the remainder of the band 20 to provide reinforcement against bending throughout the major portion of the package length; and the flat cuffs 33 and adjacent portions of the sleeves 32, which had previously been confined with the concavity 15 of the folding board 14, are snugly flatwise confined within the garment and cooperate with the local embracing band to eliminate unsightly bulges which also tend to obstruct application of the wrapper, and to produce a highly aesthetic and abundantly reinforced package such as shown in Fig. 10, without utilizing complete shirt envelopes or reinforcing inserts.

From the foregoing detailed description it will be apparent that my present invention provides an improved and highly attractive folded shirt package and an improved method of and apparatus for producing such packages in rapid succession. The curved elongated folding member or board 14 causes the shirt folds to be stretched taut transversely of the garment so that when the wrapper band 20 is finally applied and the board is withdrawn, the shirt flattens and is stretched out laterally with the spreading band and the production of wrinkles and bulges is entirely avoided so that a smooth and dressy finish results. While the convex surface 16 of the folding member is of importance in eliminating wrinkles, the concavity 15 of this folding device is also of importance in properly positioning the sleeves 32 and cuffs 33 so as to eliminate bulges which tend to obstruct advancement of the wrapper band while being applied; and although the width of the curved folding board 14 is less than that of the final packages, the difference is due to the flattening action of the resilient bands. The boards 14 may be of any desired shape, length and width and need not necessarily be provided with guide wires 17 as shown.

The improved wrapper bands 20 may be readily produced in quantity from cardboard or similar strips or sheets and with minimum waste of stock and may also be formed relatively narrow in order to reduce the cost of production to a minimum. Although the use of the collar protecting plate 25 aids in reinforcing the shirt collar 38 and in keeping the narrow band 20 in proper position, this plate 25 and the panel 26 may be omitted, but the addition of the apron projection 27 which extends downwardly a considerable distance below the front portion of the band, is desirable in order to reinforce the package against undesirable bending. A relatively narrow band 20 may therefore be utilized to effectively reinforce both the rear lower portion and the front upper collar portion of each folded shirt, and a minimum amount of stock is used in the production of these narrow retainer bands. My improved method and apparatus have proven highly advantageous and successful in actual use, and are especially useful in laundries for the purpose of folding and packing freshly laundered shirts and the like.

It should be understood that it is not desired to limit this invention to the exact steps of the method or to the precise details of construction of the apparatus herein described and illustrated, for various modification within the scope of the appended claims may occur to persons skilled in

the art; and it is also contemplated that specific descriptive terms employed herein be given the broadest possible interpretation consistent with the disclosure.

I claim:

1. The method of wrapping a shirt, which comprises, positioning the flattened and distended shirt with its buttoned bosom portion lowermost and with the flattened sleeves outstretched and the cuffs distended, bending the bosom and the superimposed back portions laterally to predetermined definite curvature and maintaining said bosom and back portions thus curved to provide a concavity extending longitudinally of the back while initially folding the sleeves inwardly to dispose the flattened cuffs lengthwise and centrally within the concavity, folding the opposite side portions of the shirt and the initially folded adjacent sleeve portions inwardly into the concavity to produce an elongated folded assemblage of definite width and subsequently folding the lower portions of the shirt transversely and superimposing the same over the inwardly folded sleeves and side portions within the concavity, slipping a continuous band wrapper over the transverse fold and along the folded shirt toward the collar, and finally releasing the pre-curved bosom and back portions to allow the completely folded shirt to spread laterally within the band.
2. The method of wrapping a shirt, which comprises, positioning the flattened and distended shirt with its buttoned bosom portion lowermost and with the flattened sleeves outstretched and the cuffs distended, definitely bending the bosom and the superimposed back portions laterally to predetermined curvature and maintaining such curvature to provide a concavity in said portions while folding the sleeves inwardly to dispose the flattened and distended cuffs lengthwise within the concavity, folding the opposite side portions of the shirt inwardly into the concavity to produce an elongated folded assemblage of definite width and subsequently transversely folding the lower portions of the shirt upwardly and into the concavity, applying a continuous band wrapper about the curved bosom portion and the shirt portions within the concavity, and finally releasing the pre-curved bosom and back portions to allow the completely folded shirt to spread laterally within the band.
